(57) **CLAIM**

The ornamental design for a wearable activity tracker, as shown and described.

DESCRIPTION

1. Wearable activity tracker

1.1 : Top, front, right-side perspective view

1.2 : Bottom, front, left-side perspective view

1.3: Front view

1.4: Left view

1.5: Right view

1.6: Top view

1.7: Bottom view

1.8: Cross-sectional view

1.9: Perspective view

1.10: Perspective view

The broken lines shown in reproductions 1.1-1.10 represent portions of the wearable activity tracker and form no part of the claimed design; a rear view is omitted because it is a mirror image of reproduction 1.3; reproduction 1.8 is a cross-sectional view taken from reproduction 1.4; reproduction 1.9 shows the wearable activity tracker in a state of use and reproduction 1.10 shows the wearable activity tracker in another state of use. The other broken lines in reproductions 1.9 and 1.10 represent environmental subject matter only and form no part of the claimed design.

1 Claim, 10 Drawing Sheets
